CLAIM

USPC **D15/139**

The ornamental design for a configurable caged ball insert for a downhole tool, as shown and described.

(58) **Field of Classification Search**

DESCRIPTION

USPC D8/70, 71; D15/21, 138, 139, 140; 166/118, 133, 134, 170, 173, 206, 166/244.1, 316, 318, 332.1, 336, 373, 375, 166/376, 381, 386, 387; 175/317; 294/86.3; 340/854.4

FIG. 1 is a perspective view of a configurable caged ball insert for a downhole tool;

See application file for complete search history.

FIG. 2 is a bottom plan view thereof;

(56) **References Cited**

FIG. 3 is a front side plan view thereof, wherein the front side plan view and the back side plan view are identical;

U.S. PATENT DOCUMENTS

FIG. 4 is a top plan view thereof;
